[57] **CLAIM**

The ornamental design for a adjustable wireform lamp holder for track lighting fixture, as shown and described.

DESCRIPTION

FIG. 1 is a front, right side perspective view of an adjustable wireform lamp holder for track lighting fixture showing our new design;

FIG. 2 is a right side elevational view thereof, the left side being a mirror image;

FIG. 3 is a front elevational view thereof;

FIG. 4 is a rear elevational view thereof;

FIG. 5 is a top plan view thereof;

FIG. 6 is a bottom plan view thereof.

The lamp and track mount are shown in broken lines for illustrative purposes only.
